(57) **CLAIM**

The ornamental design for a guitar body, as shown and described.

DESCRIPTION

FIG. 1 is a perspective view of a guitar body showing my new design;

FIG. 2 is a front elevational view thereof;

FIG. 3 is an enlarged front elevational view thereof;

FIG. 4 is an enlarged rear front elevational view thereof;

FIG. 5 is an enlarged left side elevational view thereof;

FIG. 6 is an enlarged right side elevational view thereof;

FIG. 7 is an enlarged bottom plan view thereof; and,

FIG. 8 is an enlarged top plan view thereof.

The broken line portions of the disclosure are for illustrative purposes only and form no part of the claimed design.
